UNITED STATES PATENT OFFICE.

SIMON WILLARD, OF CINCINNATI, OHIO.

BEDSTEAD.

Specification of Letters Patent No. 11,449, dated August 1, 1854.

To all whom it may concern:

Be it known that I, SIMON WILLARD, of the city of Cincinnati and county of Hamilton and State of Ohio, have invented a new 5 and useful Improvement in what I denominate Flanged Bedsteads; and I do hereby declare that the following is a full and exact description thereof, reference being had to the accompanying drawings, forming part 10 of this specification, and to the letters of reference marked thereon.

The nature of my improvement consists in constructing the bedstead in such a manner as to get the greatest possible amount of 15 strength out of a given quantity of material employed in making the bedstead. It consists of four flanged iron posts and one, two or more bed sustainers, or boxes in which the mats are laid for sleeping on.

20 The peculiar construction of the bedstead renders it very handy to take down and, can be done on the shortest notice and the whole packed away in a space not larger than the two bed supporters when laid together. The posts are laid on the inside of 25 the boxes or bed supporters together with the mattress and bed clothing and the boxes laid together then and stowed away in suitable places.

30 This form of bedstead is peculiarly adapted to steam boats and other vessels—where there is not a sufficient number of berths owing to its readiness of being set up and attached together in its parts and when 35 taken down can be packed together in such a small space, which will render it quite handy in packing them away and require but little room.

40 To enable others skilled in the art to make and use my improvement I will proceed to describe its construction and operation by referring to the accompanying drawings, which make part of this specification and to the letters of reference marked thereon.

45 Similar letters are made to refer to corresponding parts.

Figure 1, is a perspective view of the bedstead in a complete state, representing two bed boxes or supporters connected to the 50 flanged post. Fig. 2, is a transverse sectional view of the improved bedstead, showing a section of the supporters or boxes and the manner of holding them to the posts by means of rods. Fig. 3 is a top view or plan 55 showing the end of the posts and their peculiar formation. Fig. 4 is an inside view

of one of the flanged posts drawn separate, with flanges attached for supporting two boxes and Fig. 5 represents the inside view of a post drawn separate with flanges attached sufficient for supporting four bed boxes or supporters. Fig. 6 represents a perspective view of two bed supporters laid together with their bottoms turned outward and the posts of the bedstead and bed clothing placed within them for packing away when not in use. 60 65

The material as before stated used for constructing my bedstead is sheet iron.

a, a, represent what I denominate the bed supporters—made from two to seven feet long and of a suitable width to suit one or more persons to lie in—the edges of the supporters will be ornamented and strengthened by turning them in and furnishing 70 them with iron wire as represented at *c, c, c, c.* The supporters are connected to the posts *B* at their corners or angles by riveting flanges *f, f*, in the angles of the posts on the inside as represented in the different 75 drawings and more particularly in Figs. 4 and 5. There are holes made through these different flanges and the corners or angles of the bed supporters for the purpose of connecting them together with iron rods as 80 represented in Fig. 2, by the letters *R, R.* These rods may be made sufficiently long to extend the whole length of the post—or they may be attached together with short rods 85 sufficiently long to connect but one corner of 90 the supporter to the post. The present plan is furnished with connecting rods long enough to connect the different supporters with one rod, as before mentioned. 95

g, are flanges riveted or otherwise attached to the bottom of the posts for attaching the caster, *d*, to,—as represented in Figs. 2, 4 and 5. Any other mode equivalent may be used for attaching them. 100

The flanged posts are stiffened and ornamented by turning their edges out as represented at *c, c, c, c*, the same as before described—pertaining to the bed supporters.

The post can be made of quite light iron and will be strengthened by the manner of attaching the supporting flanges *f* to their inside as represented in the different drawings, which will prevent them from springing open or longitudinally. The supporting flanges, *f*, as before stated being attached to the post by means of rivets or any other way equivalent may be used, which 105 110

act at the same time as stiffeners to the posts.

What I claim as my invention and desire to secure by Letters Patent, is—

- 5 Constructing the bedstead of sheet metal posts (B) bent longitudinally at right angles, to which are secured transverse flanges (f), and of a sheet metal sustaining box, or boxes, (a) which is supported, at its cor-

ners, by said flanges, and secured in place 10 by rods (R) passing down through both the flanges and sustaining box; arranged and combined substantially in the manner and for the purposes herein set forth.

SIMON WILLARD.
